UNITED STATES PATENT OFFICE.

JOHN SCHNEIDER AND HENRY SCHNEIDER, OF ANN ARBOR, MICHIGAN.

DESIGN FOR A HOOD AND COWL-DASH ATTACHMENT FOR AUTOMOBILES.

47,307.

Specification for Design.

Patented May 4, 1915.

Application filed January 19, 1915. Serial No. 3,182. Term of patent 3½ years.

To all whom it may concern:

Be it known that we, JOHN SCHNEIDER and HENRY SCHNEIDER, citizens of the United States, residing at Ann Arbor, in the county of Washtenaw and State of Michigan, have invented a new, original, and ornamental Design for Hood and Cowl-Dash Attachment for Automobiles, of which the following is a specification, reference being had to the accompanying drawings.

Figure 1 is a perspective view of the design. Fig. 2 is a top plan view of the same.

Fig. 3 is a side elevation. Fig. 4 is a front elevation of the invention. Fig. 5 is a rear elevation.

What we claim is:

The ornamental design for a hood and cowl dash for automobiles substantially as shown.

JOHN SCHNEIDER.
HENRY SCHNEIDER.

Witnesses:

PAUL HAINES,
EMANUEL FREY.
